LOCKET CONSTRUCTION

Oscar Frank Placco, Cranston, R. I., assignor to
Cohn & Rosenberger, Inc., New York, N. Y., a
corporation of New York

Application June 26, 1939, Serial No. 281,058

6 Claims. (Cl. 63—19)

My present invention relates to the jewelry art, and has specific reference to a novel hinge arrangement for a locket.

It is the principal object of my invention to provide a hinge arrangement for a locket, which permits opening of the locket cover to a predetermined degree, and releasable retention of the opened cover at the predetermined open position.

It is a further object of my invention to provide a construction which may be utilized for a jewelry ornament having movable parts, so as to permit relative setting of the parts at any selected angular position.

With the above and other objects and advantageous features in view, my invention consists of a novel arrangement of parts more fully disclosed in the detailed description following, in conjunction with the accompanying drawing, and more specifically defined in the claims appended thereto.

In the drawing:

Fig. 1 is a plan view of the novel locket arrangement, the cover parts being in closed position;

Fig. 2 is a view similar to Fig. 1, the cover parts being in open position;

Fig. 3 is an enlarged detail of the novel hinge construction;

Fig. 4 is a section on the line 4—4 of Fig. 3;

Fig. 5 is a plan view of a jewelry ornament having movable sections; and

Fig. 6 is a section on the line 6—6 of Fig. 5.

It has been found desirable to provide a locket arrangement which has a hinge connection between the cover part and the locket body, so arranged that the cover parts may be opened to a predetermined selected position with respect to the locket body, and releasably retained in the selected position. To this end, I have provided a novel hinge arrangement which permits the cover part to be releasably latched at different angular positions with respect to the locket body.

Referring to the drawing, a locket arrangement 10 is illustrated as having a central body portion 11, a half cover portion 12 extending the entire length of the body portion, and two sectional cover portions 13 and 14 which are independently movable, as illustrated in Fig. 2. The body portion 11 is provided with spaced ears 15 at each side thereof, for accommodating cover pivot pins 16, and is further provided with tongue elements 17, positioned as for example illustrated in Fig. 2, and shaped as shown in section in Fig. 4, which are serrated or formed to provide a plurality of latch recesses or detents 18 along the length

thereof. Each cover portion is preferably made of resilient material, to permit the strike up of a spring finger 19 which is positioned to cooperate with the detents 18, see Fig. 4, whereby an opening movement of the cover portion 13 ratchets the spring finger 19 over the detents 18 until a desired angular relation to the locket body portion 11 is obtained, the engagement of one detent 18 and the end of the tongue 19 serving to releasably maintain the cover portion in its set open position. If the cover portion be made of non-resilient material, a separate spring finger may be secured by any desired means to the inner surface of the cover portion. The operating parts may be concealed from view, if desired, by suitably designing the body portion and the cover portion.

The above described arrangement thus provides a readily manufactured and assembled locket, which has one or more cover portions hinged thereto, the cover portion being movable so as to remain open to a desired degree with respect to the body portion of the locket. Obviously, the arrangement of the parts may be reversed, without changing the function and operation thereof.

The novel invention may be applied to any suitable article of jewelry. For example, an article of jewelry 20 is illustrated in Fig. 5, having four separate leaves 21, each of which are hinged, as shown in Fig. 6, to a common base 22. The base 20 is preferably provided with one or more detent tongue elements 23, and the corresponding leaves are provided with spring fingers 24 to releasably engage with the recesses of the serrated tongues 23. In the embodiment illustrated in Fig. 5, each leaf may be swung so as to stand at a desired angle with respect to the base 22 and to the other leaves. The base 22 may have a pin or other attachment member 25 for fastening to the clothing of the wearer.

While I have described a specific constructional embodiment of my invention, it is obvious that changes in the arrangement and relative positioning of the parts, and in the size and the materials used, as well as in the ornamentation thereof, may be made to suit the requirements for different jewelry articles, without departing from the spirit and the scope of the invention as defined in the appended claims.

I claim:

1. In a locket arrangement, a body portion, a cover portion hinged thereto, and means on said portion cooperating to releasably retain said cover portion in adjusted angular relation to said body portion.

50

55

2. In a locket arrangement, a body portion, a cover portion hinged thereto, and means comprising a spring finger on one portion and cooperating detents on the other portion cooperating to releasably retain said cover portion in adjusted angular relation to said body portion.

3. In a locket arrangement, a body portion, a cover portion hinged thereto, and means comprising a spring finger on the cover portion and cooperating detents on the body portion cooperating to releasably retain said cover portion in adjusted angular relation to said body portion.

4. In an article of jewelry, a base portion, an ornament portion hinged to said base portion, and means on said portions cooperating to releasably retain said ornament portion in adjusted angular relation to said ornament portion.

5. In an article of jewelry, a base portion, an ornament portion hinged to said base portion, and means comprising a spring finger on one portion and cooperating detents on the other portion cooperating to releasably retain said ornament portion in adjusted angular relation to said ornament portion.

6. In an article of jewelry, a base portion, an ornament portion hinged thereto, and means comprising a spring finger on the ornament portion and cooperating detents on the base portion cooperating to releasably retain said ornament portion in adjusted angular relation to said base portion.

OSCAR FRANK PLACCO. 18
